US00D922010S

(12) **United States Design Patent** (10) **Patent No.:** **US D922,010 S**
Lin (45) **Date of Patent:** **** Jun. 8, 2021**

(54) **VACUUM CLEANER**

(71) Applicant: **DONGGUAN SOGOODE COMPUTER SYSTEM CO., LTD,**
 Dongguan (CN)

(72) Inventor: **Fengee Lin**, Shenzhen (CN)

(73) Assignee: **DONGGUAN SOGOODE COMPUTER SYSTEM CO., LTD,**
 Dongguan (CN)

(**) Term: **15 Years**

(21) Appl. No.: **29/758,518**

(22) Filed: **Nov. 16, 2020**

(51) LOC (13) Cl. **15-05**

(52) U.S. Cl.

USPC **D32/18**

(58) **Field of Classification Search**

USPC D32/12, 15, 18, 21, 22, 31, 34

CPC A47L 9/1666; A47L 9/02; A47L 9/0081;

      A47L 9/24; A47L 5/24; A47L 9/246;

      A47L 5/26; A47L 9/2873; A47L 9/106;

(57) **CLAIM**

The ornamental design for a vacuum cleaner, as shown and described.

DESCRIPTION

FIG. 1 is a perspective view of a vacuum cleaner showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 3;

FIG. 11 is an enlarged top plan view of the vacuum cleaner; and,

FIG. 12 is an enlarged bottom plan view of the vacuum cleaner.

The broken lines in the drawings depict portions of the vacuum cleaner that form no part of the claimed design.

1 Claim, 12 Drawing Sheets
